FLASHER DEVICE

Joseph Schmidinger, Long Island City, N. Y.

Application March 3, 1936, Serial No. 66,814

9 Claims. (Cl. 200—88)

My present invention relates to thermoresponsive electric switches or flashers, and comprises an improved device of this character that is commercially practicable; being relatively simple and economical to manufacture and of sturdy construction. The invention includes also a novel circuit arrangement including as one element thereof the improved flasher device.

The improved flasher is of the type disclosed and claimed in my prior Patent No. 1,979,349, dated November 6, 1934, and in U. S. Patent No. 1,998,823, dated April 23, 1935, issued on the joint application of C. C. Bohner and myself.

The new flasher, like those of the above-mentioned prior patents, includes an expansible wire which when heated by the passage of electric current therethrough permits closure of contacts of which one is carried by the armature of a magnet; the closure of the contacts shunting the wire and causing cooling thereof with consequent opening of the contacts. In the patented devices a resilient member, connected with the armature of the magnet provides a biasing means for causing closure of the contacts upon expansion of the wire.

In the present construction, a separate biasing member or spring is not required because of the novel armature construction which incorporates therein the biasing function of the spring of the former devices. The improved form of armature not only thus eliminates one heretofore important element but also improves the operation of the devices as a whole by providing a wiping action of one contact upon another just prior to a snap action opening thereof.

Another feature of the present invention is an improved anchoring means for the end of the expansible wire remote from the armature which means permits of ready adjustment of the tension of the wire during or after assembly of the device.

Other novel constructional features of the improved device include the mounting for the fixed contact and the supporting bracket and base for the operating parts of the device.

For an understanding of the novel features of my present invention reference may be had to the accompanying drawings of which:

Fig. 1 is a side view, partly in section, of a flasher embodying the invention,

Fig. 2 is a view taken along the line 2—2 of Fig. 1,

Fig. 3 is a plan view taken along the line 3—3 of Fig. 1,

55 Figs. 4 and 5 are enlarged detailed views show-

ing the armature construction and illustrating the operation thereof,

Fig. 6 is a side view, partly in section, of a device constructed according to the invention and adapted to control more than one circuit,

Fig. 7 is a plan view taken along the line 7—7 of Fig. 6,

Figs. 8, 9 and 10 are circuit diagrams illustrating various uses of the new flasher devices.

The flasher illustrated in Figs. 1 to 5, inclusive, comprises the electromagnet coil 2, the core 4, armature 6, expansible wire 8 connected at one end with the movable end of the armature 6 and at its other end through a load resistance 10 and supporting conducting wire 12 with the fixed contact 14 carried on the wire 12 and with one end of the coil 2, an insulating base 16 upon which the parts are mounted and through which electrical connections are made, and a suitable cover 18 secured to the base 16 and completely enclosing the operating parts. A bracket 20 supports the entire flasher mechanism upon the base.

The bracket 20 is so shaped as to provide two horizontal portions at different levels and one vertical portion. The lower horizontal portion of the bracket rests upon the base 16 and is clamped thereto by a metal piece 22 which with a screw 23 forms one terminal of the device. The upper horizontal portion extends beneath the core 4, and is provided with a punched up button 24 which cooperates during operation of the device with the armature, as hereinafter described. An extension of the upper horizontal portion of the bracket is provided with an aperture 25 through which passes the wire 8. A glass bead 26, fused about the wire 8 at a point beneath the aperture 25, serves to maintain the wire under tension and to insulate it from the bracket. Adjustment of the tension of wire 8 may be readily effected by slight bending of the horizontal extension of bracket 20. In devices relying for operation upon definite but small movements, it is of paramount importance that even very slight relative dislocation of parts be avoided. The above described insulated anchoring bead and support for wire 8 is thus of particular value because it insures positively against any change in the normal position of armature 6. Also of importance is the fact that automatic machinery may be used in the assembly of this part of the device. The vertical portion of bracket 20 serves to support core 4 which is welded thereto.

The armature 6 extends vertically along one side of the core 4 and has an extended relatively resilient tail portion which curves around the

lower corner of the core and extends over and engages the button 24 of bracket 20. The end of the tail portion of the armature is welded to the lower center of the core and the upper free 5 end of the armature carries a contact 28 for engagement with contact 14. To increase magnetic attraction between armature and core, without substantially adding to the weight of the armature, the armature is constructed with 10 10 outstanding wall portions 29.

The core 4 is in the general shape of an I with relatively enlarged upper and lower portions and a restricted center portion about which the coil 2 is wound. The upper portion of the core is 15 provided with a U-shaped slot which receives and has welded thereto a metal eyelet 30. The wire 12 which serves both as a conductor and as a support for the fixed contact 14 is mounted in a short length of glass tubing 32 which is fused 20 onto the wire and also to the eyelet 30, to provide an insulated mounting for the wire. In assembling this portion of the device, wire 12 is passed through the glass tubing 32 and eyelet 30, the eyelet is then welded to the core and the tubing 25 simultaneously fused to the wire 12 and to the eyelet. The short end of wire 12 is then welded to an end of coil 2, the contact 14 is welded to the wire and the wire bent around into a loop to bring the contact 14 into alignment with contact 28 on armature 6. After the upper end of 30 resistance 10 is welded to wire 12 the distance between contacts may be adjusted while current is passed through the device, by diminishing or increasing the size of the loop into which the 35 wire 12 is bent.

When the device has been assembled and the contact gap and tension of wire 8 adjusted as above described, a suitable cover 18 is positioned about the device and secured either permanently 40 or detachably to the base 16. In the particular embodiment of the device illustrated in Figs. 1 to 3, the cover 18 is shown as permanently secured to the base by means of a sleeve 34; the sleeve being crimped over the flanged lower end 45 of the cover and being provided with an annular shoulder engaging the under surface of the base.

The button 24 acting upon the under side of the tail portion of armature 6 tends normally to 50 move the armature into contact closing position against the tension of wire 8. The button 24 also serves to mechanically protect the weld between core and armature. When the wire is cold the tension of wire 8 is sufficient to prevent closure 55 of the contacts and the parts are as shown in Fig. 1 and in full lines in the enlarged detail view of Fig. 4. When wire 8 becomes heated by the passage of current therethrough, its expansion permits the armature to move to contact 60 closing position indicated in dotted lines in Fig. 4. The closure of contacts 14 and 28 shunts wire 8 and resistance 10, the circuit then being from terminal 22 through bracket 20, core 4, armature 6, contacts 28 and 14, and coil 2 to the 65 other terminal of the device, indicated in Fig. 2 as a metal piece 36 to which one end of coil 2 is welded. Contraction of wire 8 upon its shunting by contacts 28 and 14 first causes the armature to move downward into the position illustrated 70 in Fig. 5. This downward movement is accompanied by a wiping action of contact 28 upon contact 14 and by a buckling of the tail portion of the armature about the button 24. When the buckling of the spring-like tail portion 75 becomes sufficient to overcome the magnetic

attraction of the core upon the armature, the armature snaps out into the normal open position with a positive opening of the contacts and consequent minimum of sparking. Upon opening of the contacts current flows from terminal 5 22 and armature 6 through wire 8 and resistance 10 to the coil 2 and terminal 36 (assuming an electromotive force applied across the terminals) and the consequent expansion of wire 8 causes the above described cycle of operations to be repeated with alternate increase and decrease of current through any circuit connected in series with the device.

It will be apparent from the above description that the new device may be readily assembled, 15 entirely by welding, and cheaply manufactured, that it is rugged and positive in action and yet extremely sensitive and quick acting. The armature construction and mounting upon the core provides a magnetic circuit which opens at one 20 place only, and gives the proper delayed but positive opening of the contacts; the bracket construction with its pushed up button cooperating with the armature during operation, provides a support for the device, and also an adjustable 25 means for anchoring wire 8 and the insulated support means for the fixed contact carrying member provides a simple means for adjusting the spacing of the contacts.

In Figs. 6 and 7 is illustrated an embodiment of 30 the invention which differs from that of Figs. 1 to 5 primarily in the addition of a second armature and a second pair of contacts controlled thereby. In Figs. 6 and 7, such parts of the device as are substantially identical with those already described in connection with Figs. 1 to 5, are indicated by the same reference numerals.

The device of Figs. 6 and 7, like that of Figs. 1 to 5, includes the coil 2 wound about the core 4, armature 6, expandible wire 8, ballast resistance 10 and contacts 14 and 28; the operating circuit, when the contacts are open being the same as heretofore described. In addition, the device includes a second armature 38 which carries a contact 40, a fixed contact 42 mounted on a supporting wire 44 in position to be engaged by contact 42, and a terminal 46 on the base 16 electrically connected by a lead 47 and the supporting wire 44 with contact 42. The armature 38 which is preferably constructed like armature 6, is secured at 50 its lower end to the core 4 in such manner as to tend to move to contact opening position; a stop 48 secured to the upper portion of the core 4 being provided to limit its outward movement. The opening action of armature 38 is such that when 55 contacts 28 and 14 are out of engagement and the normal operating potential difference is applied across terminals 36 and 22, the magnetic attraction upon the armature will be insufficient to move it into contact closing position but when 60 contacts 28 and 14 are in engagement and wire 8 and resistance 10 are consequently shunted from the circuit of coil 2, the armature 38 will be moved into position to close contacts 40 and 42. Thus 65 armatures 38 and 6 will move in timed relation, the one to open its circuit and the other to vary the series resistance of its circuit.

The devices above described may be advantageously employed wherever it is desired to vary the current of a circuit periodically or to open a circuit periodically. In the circuit diagram of Fig. 8 the device of Figs. 1 to 5 operates not only to flash lamps connected in series therewith but also as a relay to cause indications of the condition of the circuit to be given. In Fig. 8 a pair of lamps A 70 75

might be two signal lights on one side of a truck for indicating a left turn, a pair of lamps B might be the two signal lights on the other side of the truck for indicating a right turn. Lamp P may be 5 a small signal lamp on the dashboard. Lamps A and B are connected, through opposite poles of a manually operable switch 49, with terminal 36; and lamp P, when the switch is closed in either 10 position, is connected in parallel with either lamps A or lamps B. A suitable source of electromotive force E, presumably the truck storage battery, is connected to terminal 22. In operation, if the 15 driver wishes to turn left, he throws switch 49 to connect lamps A and lamp P into the circuit. Current will then flow from battery E through 20 armature 6, wire 8, resistance 10, coil 2, switch 49 and lamps A and P in parallel to ground. This current, because of the inclusion in the circuit of wire 8 and resistance 10 will be insufficient to 25 cause the lamps to reach incandescence. As soon, however, as wire 8 becomes heated, its expansion will permit armature 6 to move to contact closing position. The increased current due to the shunting of wire 8 and resistance 10 lights lamps A and 30 lamp P.

When wire 8 cools, its contraction causes the opening of contacts 28 and 14, and the consequent dimming of lamps A and P. This cycle continues so long as switch 49 is maintained in position to 35 include lamps A in the circuit. Should either of lamps A burn out the current through coil 2 will be reduced and consequently the holding power of the electromagnet will be reduced. This results in a more rapid operation of the device as a whole, so that the driver of the truck, upon seeing lamp P 40 flash more rapidly, is informed that one of his rear signal lamps is out of commission. Should both lamps A be burned out, the lamp P will burn steadily, drawing insufficient current to cause 45 heating of wire 8 to a point where the contacts can be closed. If a short circuit should develop, lamp P will be extinguished. Thus the pilot lamp will indicate to the driver the condition of the signal lamp circuit, anything other than the normal rate of flashing of the pilot lamp indicating something wrong. The operation of the circuit when switch 49 is thrown into position to include 50 lamp B instead of lamps A in the circuit, is of course, identical with that already described.

Where but two indications are to be given by a signal lamp, then, in the circuit of Fig. 8, the device of Fig. 6 could be used with lamp P permanently connected to terminal 46 and lamps A and B connected, as in Fig. 8, through the switch 49 55 with terminal 36. With such an arrangement, when either or both lamps A burn out the circuit of the signal lamp P will be opened, and similarly for lamps B.

Where indications of a variation in the load 60 is not necessary or desired, as for example where it is desired to flash sometimes one number of lamps and sometimes another number of lamps, the device of Fig. 6 connected as shown in the circuit of Fig. 9, may be advantageously employed. In this case the lamps to be flashed, indicated at C, are connected in the circuit controlled by armature 38 and a constant resistance 65 50 of suitable magnitude is connected to terminal 36. A switch 52, which may be manually or automatically operated, is provided in the battery circuit. For example, the circuit of Fig. 9 might be used in pin-ball machines where the tripping of the switch 52, effected by suitable mechanism, will automatically flash the lamps C 70 so long as the switch is closed. The number of

lamps C in operation will have no effect upon the rate of flashing so long as the capacity of the battery E is sufficient to carry the load.

In the device of Figs. 6 and 7 both pairs of contacts close at substantially the same time and hence lamps connected in the circuits controlled thereby would flash together. If it is desired to flash lamps, or banks of lamps, alternately, it is only necessary to replace the stop 48 by a contact electrically connected with terminal 46 5 and to eliminate contact 42 or its connection to terminal 46. In Fig. 10 such a modified device is diagrammatically illustrated and connected to flash lamps D and L alternately. In Fig. 10 lamp D is connected through terminal 46 with a contact 54 positioned to be engaged by a contact 56 on armature 38 when the armature is in its normal open position and lamp L is connected through terminal 36 with one end of the coil 2. A switch 58 controls the operation of the device. Upon closure of the switch, lamp D will first light while lamp L will burn but dimly, if at all, because it is in series with wire 8 and resistance 10. Upon expansion of wire 8, armature 6 will move to contact closing position when wire 8 25 and resistance 10 are shunted. This increases the current through lamp L sufficiently to cause it to shine brightly and also increases the magnetic attraction of coil 2 upon armature 38 sufficiently to cause it to move contact 56 out of 30 engagement with contact 54. Consequently the lamps D and L will flash alternately as wire 8 expands and contracts.

The improved flasher has now been described and examples given of its use in the control of lamps. Obviously additional applications of the flasher are possible and will be apparent to those skilled in the art. Certain novel constructional features of the improved flasher might be employed without the other specific features illustrated in the drawings and various changes in circuit connections might be made without departing from the spirit of the invention.

The following is claimed:

1. A device of the character described comprising in combination a movable member having one end fixed, a contact carried by the movable end of said member, a fixed contact positioned to be engaged by said first mentioned contact, an expansible resistance wire having one end 45 secured to the movable end of said member in electrical connection with the contact carried thereby and its other end electrically connected with said fixed contact, and insulated anchoring means for maintaining said wire under tension, whereby said wire upon contraction moves said member out of contact closing position, said insulated means including an arm having an aperture therein for passage of said wire therethrough and an insulating bead fused about said 50 wire and engaging said arm on the side thereof remote from the movable end of said member, whereby the pull of said wire upon said movable member may be adjusted by bending said arm.

2. A device according to claim 1 including 65 magnetic means with which said movable member cooperates as an armature, said fixed contact being insulatedly mounted adjacent one end of said magnetic means and the fixed end of said movable member being secured to the other end 70 of said magnetic means whereby opening of the contacts upon contraction of said wire opens the magnetic circuit at one point only.

3. A device of the class described, the combination comprising an electromagnet including a 75

core and a coil, wound thereupon, an armature secured at one end to said core, a contact carried by said armature remote from the fixed end thereof, a pair of terminals one electrically connected to said core and the other to one end of said coil, a fixed contact electrically connected to the other end of said coil and positioned to be engaged by said armature carried contact, an expansible resistance wire electrically connected across said contacts, said wire having one end secured to the movable end of said armature, and insulated anchoring means for maintaining said wire under tension, whereby said wire, upon contraction, moves said armature out of contact closing position.

4. A device according to claim 3 wherein one end of said core has a U-shaped slot therein, and wherein a wire insulatedly mounted in said slot, has welded thereto said fixed contact and one end of said coil, said last mentioned wire being formed into a loop whereby adjustment of the spacing between contacts may be effected by varying the dimensions of said loop.

5. The device according to claim 3 including a second armature having one end secured to said core and carrying a contact at the movable end thereof, a second fixed contact positioned to be engaged by the contact carried by said last mentioned armature and a third terminal electrically connected with said last mentioned fixed contact, said last mentioned armature having a resilient portion normally tending to move the armature into contact opening position.

6. A device of the character described comprising in combination an electromagnetic coil, an armature cooperating therewith and biased to retracted position, a contact carried by said armature, a fixed contact positioned to be engaged by said armature carried contact in one position of said armature, and means for intermittently varying the current through said coil so as to cause said armature to open and close said contacts intermittently, said means including a source of electromotive force, a second armature and a contact carried thereby, a fixed

contact positioned to be engaged by the contact carried on said last mentioned armature when the armature is in attracted position and an expansible resistance wire connected across said last mentioned contacts so as to be shunted when the contacts are closed, said wire being connected under tension to said last mentioned armature whereby when the wire contracts it moves said armature to contact opening position.

7. A device according to claim 6 wherein the first mentioned fixed contact is positioned to be engaged by the contact carried by said first mentioned armature when that armature is in attracted position whereby a circuit connected to said fixed contact will be closed when the current through said coil is increased by the shunting of said wire and will be opened when the current through said coil is decreased by the series resistance of said wire.

8. A device according to claim 6 wherein the first mentioned fixed contact is positioned to be engaged by the contact carried by said first mentioned armature when that armature is in retracted position whereby a circuit connected to said fixed contact will be opened when the current through said coil is increased by the shunting of said wire and will be closed when the current through said coil is decreased by the series resistance of said wire.

9. A thermo-responsive switch comprising a biased member adapted to assume different positions, contacts positioned to occupy one relative position when said member assumes its biased position, an expansible wire anchored at one end to said member and normally holding said member in another relative contact position, and insulated anchoring means for maintaining said wire under tension, said insulated means including an arm having an aperture therein for the passage of the wire therethrough and an insulated bead fused about said wire and engaging said arm on the side thereof remote from the connection of said wire with said member.

JOSEPH SCHMIDINGER. 45
